UNITED STATES PATENT OFFICE.

JOSEPH WARREN ANTHONY, OF LYNN, MASSACHUSETTS.

DESIGN FOR A METAL ORNAMENT.

No. 40,228.

Specification for Design.

Patented Aug. 17, 1909.

Application filed June 14, 1909. Serial No. 502,183. Term of patent 3½ years.

To all whom it may concern:

Be it known that I, JOSEPH WARREN ANTHONY, a citizen of the United States, residing at Lynn, in the county of Essex and State of Massachusetts, have invented a new, original, and ornamental Design for Metal Ornaments, of which the following is a specification, reference being had to the accompanying drawing, forming part thereof.

The figure is a plan view of a metal ornament, showing my new design.

I claim:

The ornamental design for a metal ornament, as shown.

JOSEPH WARREN ANTHONY.
